CLAIM

The ornamental design for a wire grating structure, as shown and described.

DESCRIPTION

FIG. 1 is a perspective view of a wire grating structure showing our new design;

FIG. 2 is a top plan view thereof;

FIG. 3 is a front elevation view thereof, the rear elevation view being a mirror image thereof;

FIG. 4 is a right side elevation view thereof, the left side elevation view being a mirror image thereof;

FIG. 5 is a perspective view of an alternative embodiment of the wire grating structure showing our new design;

FIG. 6 is a top plan view thereof;

FIG. 7 is a front elevation view thereof, the rear elevation view being a mirror image thereof; and,

FIG. 8 is a right side elevation view thereof, the left side elevation view being a mirror image thereof.

The uneven-length broken lines at the rear and right sides of the wire grating structure depict the boundaries of the claimed design and form no part thereof. The even-length broken lines depicting the remainder of the wire grating structure show features that form no part of the claimed design.

1 Claim, 2 Drawing Sheets
